(57) **CLAIM**

The ornamental design for a gas valve flange kit, as shown and described.

DESCRIPTION

FIG. 1 is a front perspective view of the gas valve flange kit of the present invention showing my new design; FIG. 2 is a rear perspective view thereof; FIG. 3 is a top plan view thereof; FIG. 4 is a front elevational view thereof; FIG. 5 is a side elevational view thereof; and, FIG. 6 is a rear elevational view thereof. The dotted lines shown in the figures do not form any part of the claimed design.
